EDWARD CHESHIRE, OF ST. PETERSBURG, FLORIDA

COMPOSING ROOM MACHINE

Application filed June 3, 1927. Serial No. 196,196.

The present invention relates to composing room machines.

More particularly the present invention relates to improvements in machines such as are used in the composing rooms of printing establishments. The present invention contemplates a combined machine having the functions of a router, type-high machine, drill, jig-saw and broacher, and has for one of its objects the provision of a machine occupying relatively small space, which is simple and sturdy in construction and which is well adapted to meet the needs of commercial service.

15 A further object is to provide an improved router or type-high machine which is readily adjustable and which is convenient to use.

A further object is to provide an improved type-high machine which may be accurately 20 and conveniently adjusted regardless of wear upon the cutting tool.

A further object is to provide an improved 25 jig-saw or broacher which is convenient in use, particularly with relation to convenience in changing the cutting blade.

Further objects will appear as the description proceeds.

Referring to the drawings—

Figure 1 is a view in side elevation of one 30 embodiment of the present invention;

Figure 2 is a view in side elevation from the other side of the machine shown in Figure 1;

Figure 3 is an enlarged fragmentary sectional elevation taken through the jig-saw portion of the machine;

Figure 4 is an enlarged fragmentary sectional elevation taken substantially in the plane as indicated by the arrows 4—4 of 40 Figure 1; and

Figures 5 and 6 show a detail of construction.

The numeral 10 indicates a standard mounted upon a base 11. Bolted or otherwise secured at the upper extremity of the standard 10 is a member 12 provided with two pairs of jaws or arms. The upper and lower jaws 13 and 14, respectively, on one side of the member 12 comprise the cooperating jaws of a jig-saw, broacher or the like. The

jaws 15 and 16 on the opposite side of the member 12 comprise the jaws of a router, type-high machine, or the like.

Referring first to the jig-saw portion of the machine, a motor 17 is supported in any 55 preferred manner upon the standard 10, which motor is provided with a pulley 18, which through a belt 19 drives the pulley 20, which pulley 20 is secured to the shaft 21, having bearings 22—22 supported by the 60 lower jaw 14 of the jig-saw portion of the machine. The extremity of the shaft 21 spaced from the pulley 20 is provided with the eccentric or crank 23 having the pin 24 which drives the crank arm 25. Said crank 65 arm 25 drives the pin 26 secured to the cross-head 27, which is secured upon the outer extremity of the jaw 14 in a manner to permit a reciprocating movement in a vertical direction. The crosshead 27 is provided with 70 the hook 28 adapted to engage over one extremity of the saw blade 29. The other extremity of the saw blade 29 is adapted to be engaged by the hook 30 carried by the slide 31, which slide is supported to have a reciprocating straight line movement upon the outer 75 extremity of the jaw 13. Said slide 31 is provided with the roller 32 adapted to be engaged by the outer extremity of the lever 33, which lever 33 is pivoted to have a rock- 80 ing movement with the shaft 34 as an axis. A coil spring 35, which may be anchored upon the abutment 36, biases the lever 33 in a clockwise direction, movement in said direction being limited by reason of the engagement of 85 the outer swinging end of said lever 33 with the roller 32 of the member 31, movement upwardly of which is limited by reason of the connection of the saw blade 29 with the member 27, which is pinned to the crank arm 25. 90 The numeral 37 indicates a handle which may be swingingly mounted upon the shaft 34 and which projects above the jaw 13 in a position in which it may be readily grasped. Said handle includes an arm 37A parallel with but 95 spaced from the shaft 34, which arm 37A overlies the lever 33. Said handle 37 provides means whereby the outer swinging end of the lever 33 may be depressed in opposition to the spring 35, whereby the saw blade 29 100

may be readily changed. The numeral 38 indicates a work table carried by the jaw 14, which work table is apertured as indicated by the numeral 39, whereby to permit reciprocating straight line movement of the saw blade 29.

Referring now to the router or type-high portion of the machine, the upper jaw 15 is formed to slidably receive a motor 40, which 10 motor is disposed with its axis vertical. Said motor 40 is provided with the collar or chuck 41 adapted to grip the router or type-high tool 42. The numeral 43 indicates a 15 table for supporting work to be operated upon by the tool 42. Said table 43 is carried by the shaft 44, which shaft is carried by the jaw 16 in a manner which will be described presently. A stud or studs 44A are provided for holding the table 43 against 20 displacement about the axis of the shaft 44, while permitting vertical movement of said table 43. The shaft 44 is adapted to have sliding movement in a vertical direction within the sleeve portion 45 at the extremity 25 of the jaw 16. Said sleeve portion 45 is cut away as indicated by the numeral 46, to provide access to the shaft 44, the adjacent side of which shaft 44 is provided with the rack teeth 47. Engaging with the rack teeth 47 30 is the gear 48 secured to the shaft 49, which is rotatably supported by the bracket 49A, which is releasably secured to the jaw 16 at the bottom of the sleeve portion 16 thereof, screws 49B—49B being illustrated as the 35 holding means. Rocking movement is communicated to the shaft 49 by means of the segment 50, said segment 50 being controlled by the treadle 51 operating through the cable 52. Said treadle 51 is pivoted to the 40 standard 10, as indicated by the numeral 53. It will be clear that when the outer extremity of the treadle 51 is depressed, the gear 48 will be rotated in a counterclockwise direction as the parts are viewed in Figure 4, resulting in the lifting of the shaft 44 and the table 43. In order to govern the limits 45 of travel of the table 43, adjustable means are provided which will now be described. The numeral 55 indicates a shaft having the 50 screw-threaded portion 56 and the second screw-threaded portion 57. Intermediate of the screw-threaded portions 56 and 57 is the shoulder 58 adapted to rest against the bracket 49A when the table 43 is in its lowermost position. The screw-threaded portion 56 of the shaft 55 has engagement with the threaded axial aperture 59 within the shaft 44. A hand wheel 60 is provided at the lower extremity of the shaft 55 for communicating 55 turning movement to said shaft. The shaft 44 will be held against rotative movement whereby turning of the shaft 55 will communicate a straight line movement to said shaft 44, whereby the lower limit of the table 43 will be determined. Figure 4 shows the shaft

44 in engagement with the shoulder 58, this being the lowermost position of said shaft 44. The screw-threaded portion 57 of the shaft 55 is provided with the nut 61, which nut is split in a plane transverse to the axis 70 of the shaft 55, as indicated by the numeral 62. A screw 63 is provided for adjusting the grip of said nut 61 upon the screw-threaded portion 57. By varying the position of said nut 61, the upper limit of travel 75 of the shaft 55 is determined.

In order that vibration of the table 43 may not cause a creeping of the shaft 55 whereby to result in the lowering of the table 43, means are provided for preventing turning movement of the shaft 55 relative to the shaft 44. By reference to Figure 5 it will be noted that the screw-threaded portion 56 of the shaft 55 is provided with a radial hole 64, which hole is adapted to receive the button 65, which button is spring-pressed outwardly by the spring 66. The outer extremity of the button 65 is toothed, as indicated by the numeral 67, to conform to the threads of the aperture 59 within the shaft 44. By reason of the fact 85 that the button 65 is spring-pressed outwardly against the wall of the aperture 59, creeping of the shaft 55 is effectually prevented. It will be understood, of course, that by adjusting the nut 61, the workman 90 may accurately predetermine the upper limit of travel of the table 43. This feature is useful in routing out an enclosed area, the routing being done with the treadle depressed (table up), the treadle being allowed to rise 100 when the boundary of the routed out portion is to be passed over.

Certain features of the present invention applicable to adjustment for type-high planing will now be described. A printing plate should preferably have a flat back, and usually has a standard height of .918 inch or varying from said standard by a predetermined amount. According to the present invention absolute accuracy is obtainable in 110 type-high planing regardless of wear in the planing tool. In order to provide accurate adjustment, an indicator rod 68 is provided, which indicator rod is best shown in Figure 2. Said indicator rod is mounted to swing 115 about the axis of the vertically disposed shaft 69 and is provided with the indicator 70 for indicating variations in the vertical position of the rod 68. The shaft 69 is rotatably disposed within the boss 71 located upon the jaw 15, and is resiliently held in position by means of the spring 72. Mounted upon the shaft 69 is the arm 73, said arm being adjustable along the shaft 69, which arm 120 yieldingly supports the rod 68.

In operation, a printing plate is supported in a vise 74, which is supported upon the table 43, and a planing cut is made on the rear side of said printing plate by the tool 42 to mark the cutting plane of said tool. 130

Said plate is then placed under the vertically disposed indicator rod 68. Said rod 68 is so disposed that the spring urging it downwardly is under slight tension when said indicator rod is bottomed on said planed surface. The scale on the indicator 70 is set so that zero corresponds with the needle 75 of the indicator 70, which needle is movable in response to movement in a vertical direction of the indicator rod 68. The zero position of the cutting plane of the tool is therefore determined. A standard block may be positioned between the plane surface upon which the printing plate is supported and the bottom of the indicator rod, and the hand wheel 60 is turned until the needle 75 reads zero, or a predetermined variation from zero, as desired. The table is now in proper position for a planing cut at the predetermined height. Any preferred means may be provided for locking the hand wheel once it has been set, the button 65 being indicated for this purpose.

It is intended to cover all modifications that fall within the scope of the appended claims.

What is claimed is—

1. In a machine, in combination, a standard, an arm projecting therefrom, a vertically movable table carried by said arm, rack and pinion means for raising said table, and adjustable means for governing the movement of said table relative to said one arm, said adjustable means including a screw-threaded axially reciprocable shaft, screw-threaded means cooperating with said screw-threaded shaft for determining one limit of the axial movement of said shaft, said screw-threaded means including a spring-pressed toothed button radially movable therein and adapted to engage the threads of said screw-threaded shaft.

2. In a machine, the combination of a support, a tool mounted for movement on supporting means on said support, means for controlling movement of said tool, supporting means mounted at a point removed from said first named supporting means, and a tool mounted for independent control on said last-named supporting means.

3. In a machine, the combination of a support, a tool mounted for reciprocating movement on supporting means on said support, means for imparting reciprocating movement to said tool, supporting means mounted at a point removed from said first-named supporting means, and a tool mounted for control independent of said first named tool but for associated work therewith on said last-named supporting means.

4. A router and jig-saw machine, comprising in combination, a base, a head mounted on the base, said head comprising a plurality of arms, one arm being provided with router mechanism and the other arm being provided with jig-saw mechanism, and a plurality of

supporting members extending outwardly from the base beneath the arms, one of said members being provided with mechanism for reciprocating the jig-saw, and the other of said members being provided with a vertically movable work table for cooperation with the router mechanism.

5. A router and jig-saw machine comprising, in combination, a base, a head mounted on the base, said head comprising a plurality of oppositely extending arms, router mechanism associated with one of the arms and jig-saw mechanism associated with the other of said arms, and supporting members located beneath the router extremities of the outwardly extending arms for holding work adapted to be operated upon by the router and jig-saw mechanisms, said machine being constructed and arranged to permit ready removal of the jig-saw and router whereby other and different types of tools may be mounted within the machine for cooperation with the supporting members.

6. A router and jig-saw machine comprising, in combination, a base, a head mounted on the base, said head comprising a plurality of arms, one of which is provided with router mechanism and the other of which is provided with a jig-saw mechanism, a plurality of supporting members extending outwardly from the base beneath the arms, one of said members being provided with means for imparting reciprocatory movement to the jig-saw and the other of said members being provided with a vertically movable work table for cooperating with the router mechanism, and a treadle arranged to impart vertical movement to the work table.

7. A router and jig-saw machine comprising, in combination, a base, a head mounted on the base, said head comprising a plurality of arms, one of which is provided with router mechanism and the other of which is provided with jig-saw mechanism, a plurality of supporting members extending outwardly from the base beneath the arms and separate work tables carried by the supporting members and arranged for cooperation with the jig-saw mechanism and the router mechanism said jig-saw mechanism comprising a mounting which permits easy and ready removal of the jig-saw from the machine.

8. A router and jig-saw machine comprising, in combination, a base, a head mounted on the base, said head comprising a plurality of oppositely extending arms, one of which is provided with router mechanism and the other of which is provided with jig-saw mechanism, a plurality of supporting members extending from the base member outwardly beneath the oppositely extending arms of the head, and a plurality of work tables carried by the supporting arms for cooperation with the jig-saw and router mechanism, said latter mechanism being so constructed and arranged

as to permit removal of the router tool and substitution therefor of a drilling tool.

9. A machine of the character described having, in combination, a base, an arm projecting outwardly from the top of the base, a second arm extending outwardly below the first named arm, a vertically movable table carried by the second arm, rack and pinion means for imparting vertical movement to the table, means including a treadle for operating the rack and pinion, and means for governing the extent of vertical movement of the table.

Signed at Cleveland, Ohio, this 31st day of May, 1927.

EDWARD CHESHIRE.
